US00D988896S

(12) **United States Design Patent** (10) **Patent No.:** **US D988,896 S**
(45) **Date of Patent:** **** Jun. 13, 2023**

(54) **FLAT LIGHT**

(71) Applicant: **SHENZHEN THANKSHOME TECHNOLOGY CO., LTD.**
Guangdong (CN)

(72) Inventor: **Chaoqun Zhou**, Guangdong (CN)

(**) Term: **15 Years**

(21) Appl. No.: **29/852,200**

(22) Filed: **Sep. 5, 2022**

(30) **Foreign Application Priority Data**

Aug. 18, 2022 (EP) 009151053-0001

(51) **LOC (14) Cl.** **10-06**

(52) **U.S. Cl.** USPC **D10/114.3**

(58) **Field of Classification Search**

USPC D10/118.2, 119.1-121, 113.4-114.3,
D10/114.5, 114.8, 109.1, 120-121, 111
CPC F21K 9/00; F21L 4/027; F21L 2/00; F21L
4/08; F21W 2111/00

(57) **CLAIM**

The ornamental design for a flat light, as shown and described.

DESCRIPTION

FIG. 1 is a perspective view of the flat light showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion indicated with numeric 9 in FIG. 2.

The broken lines shown in the drawings represent portions of the flat light that form no part of the claimed design.

1 Claim, 9 Drawing Sheets
